Application July 5, 1955, Serial No. 519,864

9 Claims. (Cl. 260—635)

2

containing a higher fatty alcohol ester of a fatty acid, hydrogenating the bottoms fraction to produce hydrogenation products containing the higher fatty alcohol, passing the hydrogenation products to the distillation zone together with further quantities of fat.

The ester interchange reaction may be represented by the following equation:

The present invention relates to the preparation of higher fatty alcohols and glycerine. More particularly, the invention has to do with a process for the production of higher fatty alcohols and glycerine from animal and vegetable fat, solid or liquid, e. g., tallow and coconut oil. These higher aliphatic alcohols and mixtures thereof predominating in normal primary alcohols of ten or more carbon atoms are useful as intermediates in the preparation of wetting, dispersing and foaming agents, in detergent compositions, and the like.

A known method of preparing these higher fatty alcohols includes hydrogenation of higher fatty acids. This method, however, suffers from certain disadvantages, such as formation of water in the hydrogenation step, which shortens the catalyst life; the use of large proportions of hydrogen to sweep the water from the system; a high acidity of the feed with attendant corrosion problems to equipment, and a tendency of the free acids to decarboxylate, thus giving undesirable oils. Another method involves hydrogenation of the esters of higher fatty acids and low molecular weight alcohol, e. g., methanol. However, this method also suffers from certain serious disadvantages such as the requirement of elaborate procedures for making the ester, and difficult separation problems, arising from the overlapping boiling points of the esters and the product higher fatty alcohols. This has necessitated carrying the hydrogenation essentially to completion, in order to completely remove the difficultly separable unconverted esters. A still further method of producing fatty alcohols involves the direct hydrogenation of fats. Such procedure, however, results in the loss of glycerine which is converted into such products as isopropanol.

Pursuant to the present invention, hereinafter more specifically described, the above-enumerated disadvantages are eliminated. Thus, while higher fatty alcohols are produced, recovery of glycerine in full value and in pure form is also effected. In addition catalyst life is long, and substantially no corrosion problems exist. The process of the present invention is also characterized by the absence of any decarboxylation. Separation difficulties are also obviated because of the large difference in boiling points between the hydrogenated higher fatty alcohol and unhydrogenated ester of the higher fatty alcohol. No need to hydrogenate to completion exists with the present process. In accordance with the present invention it is possible to operate over conversion ranges where hydrogenation is most rapid thus avoiding the relatively slow rates required for 100% conversion. As a result of this advantage, great savings in equipment can be effected, and the process carried out in a compact, highly effective system not possible with the known processes.

Broadly, the present invention is based on a process which involves transesterifying a fat with a higher fatty alcohol produced in accordance with the process in a distillation or transesterification zone, withdrawing from the distillation zone an overhead fraction containing the higher fatty alcohol and glycerine and a bottoms fraction

15 R and R' may be like or unlike alkyl groups, depending on the nature of the fat employed. By using high concentrations of tallow alcohols and by removing glycerine as formed the reaction will favor the products. Transesterification of the fat with the fatty alcohol occurs in the presence of an ester interchange catalyst in known fashion, e. g., litharge or lead oxide. Other known interchange catalysts can be employed, and these include tin, cadmium, zinc, and their compounds, sodium ethylate and sulfonic acids. (See the publication, "Glycerol" by

20 Miner, C. S., and Dalton, N. N., Reinhold Publishing Corporation (1953), New York, New York.)

Temperatures employed in the transesterification reaction are desirably kept below those at which substantial polymerization and decomposition of the glycerine would occur. Accordingly, a temperature of about 650° F. represents a satisfactory upper limit. Since too low a temperature retards rate of reaction, a satisfactory lower temperature limit is about 300° F. A preferred temperature range is from about 350° F. to 550° F.

25 In order to distill the glycerine and higher fatty alcohol at a practical rate low pressures of the order of 2 to 20 mm. of mercury are required in the ester interchange zone. By recycling hydrogen or other inert gases through the system a more practicable operation ensues in that there is obtained a much higher total working pressure than can be reached easily by conventional vacuum equipment. Thus, by the expedient of recycling hydrogen or some inert gas it is possible to cooperate with pressures as high as 50 to 100 mm. of mercury.

30 35 Residence time of the reactants in the ester interchange zone can be very short depending on temperature, a longer reaction time being required at the lower temperatures, and shorter residence time at the higher temperatures, too long a residence time resulting in product discoloration, and too short a residence time in low yields of glycerine. In general a residence time within about the range of 1 minute to 100 minutes will be found satisfactory.

40 45 It has also been found that the process of the invention is carried out more effectively when a stoichiometric excess of higher fatty alcohol over the glycerine is employed. Accordingly an alcohol to glycerine mole ratio greater than 3 to 1 is employed most advantageously. A top ratio of 7 moles of higher fatty alcohol to 1 mole of glycerine represents a practical upper limit.

50 55 Following the ester interchange reaction the acid esters of the higher fatty alcohols are hydrogenated in a hydrogenation zone to produce the higher fatty alcohol. This reaction may be illustrated as follows:

This reaction is exothermic in nature. High temperatures and pressures of hydrogen speed up the rate of reaction.

60 65 Suitable hydrogenation catalysts are the conventional ones employed for the hydrogenation of esters. These include the chromites of metals, e. g., copper, as shown

for example in U. S. Patent 1,839,974; such metals as cadmium, silver, tin and their oxides, as well as the oxides of zinc, chromium, magnesium and manganese; and the ruthenium-containing hydrogenation catalysts as described in U. S. Patent 2,607,807.

Hydrogenation can be effected at a temperature within about the range of 400 to 700° F. and pressures within about the range of 500 to 5000 pounds, for a period of time varying from a few minutes and longer, e. g., 60 minutes, with about 1/2% to 10% of catalyst based on the ester, the catalyst being suspended in the ester or employed in fixed bed over which the ester is passed.

In order to illustrate the practice of the invention reference is made to the accompanying drawing which is a schematic block diagram showing the zones of ester interchange, hydrogenation, separation and recycle of hydrogenation products and catalyst.

Referring now to the drawing, the fat, e. g., tallow containing the ester interchange catalyst, e. g., litharge, is fed to the top of the ester interchange zone, and the higher fatty alcohol, e. g., tallow alcohol produced in a subsequent step of the process, hereinafter to be shown, near the bottom. As the fat travels down the ester interchange zone, under interchange conditions hereinabove described, the ester interchange reaction occurs with the tallow alcohol distilling up the column forming glycerine and the tallow acid-tallow alcohol ester. At the reaction temperature, e. g., 400° F., glycerine, and excess tallow alcohol are distilled into a separator where two easily separable phases of tallow alcohol and glycerine are formed, hydrogen gas being circulated through the reactor to maintain the partial pressure necessary to distill the alcohol and glycerine at the reaction temperature. The tallow acid-tallow alcohol ester collects at the base of the ester interchange zone, whence it is passed to a catalyst separation zone, e. g., a filtering zone. The catalyst is removed from the ester and returned to the ester interchange zone, and the ester passed into the hydrogenation zone. Catalyst, e. g., copper chromite, is contacted with incoming ester and hydrogen introduced near the bottom of the hydrogenation zone, and the tallow acid-tallow alcohol ester hydrogenated under the conditions hereinabove given. Following hydrogenation, catalyst is removed from the hydrogenation products and returned to the hydrogenation zone with any catalyst make-up. The hydrogenation products containing higher fatty alcohol are conducted to the ester interchange zone for use in the ester interchange reaction earlier described.

Obviously many modifications and variations of the invention, as hereinbefore set forth, may be made without departing from the spirit and scope thereof and, therefore, only such limitations should be imposed as are indicated in the appended claims.

We claim:

1. Process for the production of higher fatty alcohols which comprises contacting a fat with a higher fatty alcohol under transesterifying conditions in a distillation zone, withdrawing an overhead fraction comprising fatty alcohol and glycerine and a bottoms fraction comprising a higher fatty alcohol ester of a fatty acid from the distillation zone, contacting the bottoms fraction with hydrogen in the presence of a hydrogenation catalyst under hydrogenating conditions in a hydrogenation zone and passing the hydrogenation reaction product into the distillation zone together with further quantities of fat.
2. Process according to claim 1 wherein the hydrogenation catalyst is a copper chromite.
3. Process for the production of higher fatty alcohols which comprises heating a fat with a stoichiometric excess of a higher fatty alcohol in a distillation zone at a temperature between about 300° and 600° F. under reduced pressure in the presence of an ester interchange catalyst, withdrawing an overhead fraction comprising fatty alcohol and glycerine and a bottoms fraction comprising a higher fatty alcohol ester of a fatty acid from the distillation zone, contacting the bottoms fraction with a hydrogenation catalyst at elevated temperatures and pressures to produce a hydrogenation product containing the higher fatty alcohols, and passing said hydrogenation product into the distillation zone together with further quantities of fat.
4. Process according to claim 3 wherein the bottoms fraction is contacted with a hydrogenation catalyst at a temperature within the range of 400° F. to 700° F. and at pressure within about the range of 500 to 5000 pounds.
5. Process according to claim 4 wherein the ester interchange catalyst is litharge.
6. Process according to claim 3 wherein the hydrogenation catalyst is a copper chromite.
7. Process according to claim 6 wherein the fat is tallow.
8. Process according to claim 7 wherein the fatty alcohol and fat is introduced into the interchange zone in a mole ratio of from greater than 3 to 1 up to 7 to 1.
9. Process for the production of higher fatty alcohols which comprises contacting a fat with a higher fatty alcohol under transesterifying conditions, fractionally distilling the transesterification reaction product to separate glycerine and fatty alcohol overhead and to produce a bottoms fraction rich in fatty alcohol ester of fatty acid, contacting the bottoms fraction with hydrogen in the presence of a hydrogenation catalyst under hydrogenating conditions and then contacting at least a major proportion of the hydrogenation reaction product with further quantities of fat under transesterifying conditions.
